UNITED STATES PATENT OFFICE

ELMER E. FREY, OF LOS ANGELES, CALIFORNIA, ASSIGNOR TO EDWARD F. LEONARD AND JOHN P. MEEHAN, BOTH OF LOS ANGELES, CALIFORNIA

UMBRELLA

Application filed April 1, 1929, Serial No. 351,636. Renewed November 6, 1931.

This invention relates to umbrellas, and an object is to provide an improved structure and arrangement of parts designed for adding rigidity to the frame and for rendering the construction of umbrellas more economical than in other types now in use.

In the consideration of this invention, reference is had to my pending application for patent on umbrellas, filed Nov. 14, 1928, Ser. 10 No. 319,355.

An object of the present invention is to provide an improved form of structure over that shown in my said pending application for patent. The improvements of the present invention primarily comprehend the provision of an improved type of gear or joint for attaching the braces to the ribs.

Other and more detailed objects of the invention may appear as the description progresses.

In the accompanying drawing,

Fig. 1 is an enlarged fragmentary section of an umbrella constructed in accordance with my invention.

Fig. 2 is a plan view of the movable sleeve with which the ribs are connected prior to the formation of the sockets in which the braces are supported.

Fig. 3 is a sectional elevation of the same. 30 Fig. 4 is a transverse section of one of the rib and brace connections on line 4—4 of Fig. 1.

Figs. 5 and 6 are, respectively, views of the same on lines 5—5 and 6—6 of Fig. 4.

As shown in the drawing, A represents the center pole, which has a reduced extension A1 at the top thereof and a shoulder A2 on which a rib supporting disk B is adapted to be held. The disk B is provided with a central circular portion B1 adapted to be secured to the portion A1 of the pole by means of brads or screws B2. The member B is initially formed as shown in Fig. 2, with a plurality of lips as at 1, 1 etc., the corresponding sides of which are straight, as at 2, while the other sides are cut on diagonal lines 3 and are provided with grooves 4 intermediate the adjacent lips.

As shown in Fig. 1, the lips 1 are adapted to be bent downwardly at B3, B3 etc., to

form sockets for pivotally receiving portions, C1, C1 etc., of the ribs C, C. The sockets B3 are substantially elongated, as are also the portions C1, so as to provide substantially long bearings for the inner ends of the ribs.

The cover D of the umbrella is fitted snugly over the member B and is held in position thereon by means of a ferrule E, which has a flange E1 overlying the inner portion of the cover and a central portion E2 adapted to be pressed into frictional engagement with the extension A1 of the pole. The cover D, as usual, is suitably attached at its outer periphery D1 to the ends of the ribs C by means of clips D2.

A sleeve F is slidably mounted on the body of the pole A and is provided at its upper end with a plurality of sockets F1, F1 etc., formed to correspond substantially to the sockets B3 of the disk B, as shown in Fig. 2. Said sleeve also has a skirt F2 which embraces the body of the pole A, and the lower edge F3 thereof is adapted to rest upon a latch G, which is fixed to the pole for holding the umbrella extended for use. The latch G, as in similar devices, serves to hold the umbrella in extended position by reason of its engagement with the edge F3 of the sleeve.

The sleeve F is pivotally connected with the ribs C by means of a plurality of braces H, H etc., which correspond in number to the sockets F1 on the sleeve and the ribs C. The braces H are provided with right angularly bent bearing portions H1 at their inner ends, which are held in the sockets F1 and correspondingly formed bearing portions H2, which are adapted to pivotally engage supporting devices J, J etc., carried in fixed position on the ribs C.

The gears J are formed of thin sheet metal with a central circular portion J1 tightly engaging and embracing the rib C in each case and flat extensions J2 and J3 which are riveted together at J4. By reference to Fig. 5, it will be noted that the portions J2 and J3 are spread apart at J6 and J7 and are apertured to pivotally receive the portions H2 of the braces H. The central portion J1 is provided with a right angularly bent lug 100

J8 which is cut away from said central portion and is disposed in spaced relation to the portion J6 so that it will engage the portions H3 of the braces H immediately adjacent the bearing portions H2.

5 The structure just described provides a suitable bearing for the braces H at the ribs and at the same time prevents the displacement of the braces from the sockets in the members J. By reason of the connection of the ribs C and braces H with the members B and F respectively, and the connection of the braces H with the members C, as shown and described, a substantially rigid structure 10 is provided for the umbrella frame which prevents the warping and twisting of the ribs.

15 Other advantages of my improved structure will readily appear to those skilled in the art.

20 What I claim is:

1. In an umbrella, in combination with a rib and a brace adapted to be pivotally attached thereto, of an attaching device frictionally supported on the rib and provided 25 with a central portion embracing the rib, and extensions therefrom provided with central bearing portions spaced apart, and another extension therefrom spaced from the bearing portion, said brace having a right angularly bent portion pivotally held in said bearing portions and adapted to engage said other extension for preventing the displacement of the brace from the bearing.

2. In an umbrella, in combination with 30 a rib, and brace pivotally attached thereto, an attaching device fixedly supported on said rib formed of sheet metal and provided with an elongated central portion embracing said rib, and extended end portions attached 35 together, transversely spaced bearings being provided centrally in said end portions and inwardly of the rib, a lug bent outwardly from said central portion and spaced from said bearings, and a right angular portion 40 formed on said rib pivotally engaging said bearings and prevented from displacement 45 therefrom by engagement with said lug.

ELMER E. FREY.
